(57) **CLAIM**

The ornamental design for a portable humidor, as shown and described.

DESCRIPTION

FIG. 1 is a top front perspective view of a portable humidor with the lid applied, according to the present invention; FIG. 2 is a front elevation view of the portable humidor of FIG. 1;

FIG. 3 is a rear elevation view of the portable humidor of FIG. 1;

FIG. 4 is a right side elevation view of the portable humidor of FIG. 1;

FIG. 5 is a left side elevation view of the portable humidor of FIG. 1;

FIG. 6 is a top view of the portable humidor of FIG. 1;

FIG. 7 is a top view of the portable humidor with the lid removed of FIG. 1;

FIG. 8 is a top perspective view of the portable humidor with the lid removed of FIG. 1;

FIG. 9 is a bottom view of the portable humidor of FIG. 1; FIG. 10 is a top perspective view of the lid removed from the portable humidor of FIG. 1;

FIG. 11 is a bottom perspective view of the lid removed from the portable humidor of FIG. 1;

FIG. 12 is a left top front perspective view of the portable humidor of FIG. 1; and,

FIG. 13 is a left top front perspective view of the portable humidor of FIG. 1, with the lid removed.

Broken lines, where present, illustrate portions of the portable humidor that form no part of the claimed design.

1 Claim, 9 Drawing Sheets
